UNITED STATES PATENT OFFICE.

JOHN R. SHANNON, OF LOWELL, ARIZONA.

FEED-WATER-HEATING SYSTEM FOR LOCOMOTIVES.

Application filed June 14, 1922. Serial No. 568,207.

To all whom it may concern:

Be it known that I, JOHN R. SHANNON, a citizen of the United States, residing at Lowell, in the county of Cochise and State 5 of Arizona, have invented certain new and useful Improvements in Feed-Water-Heating Systems for Locomotives, of which the following is a specification, reference being had to the accompanying drawings.

10 This invention relates to feed water heating systems for locomotives.

An important object of the invention is to provide a system of this character whereby the heat of the exhaust steam may be 15 utilized for heating the feed water.

A further object of the invention is to provide means for compressing the exhaust steam and injecting the same into the feed water system.

20 A still further object of the invention is to provide a system of this character which is simple in construction and arrangement, which may be readily installed in locomotives as at present constructed, and which 25 is a general improvement in the art.

A still further object of the invention is to provide a heating device of this character receiving water from the boiler of the locomotive and returning the same to the boiler 30 and subjecting the same during its passage through the heater to the action of the exhaust vapors from the cylinders of the engine.

An additional object of the invention is 35 to provide a compressor for injecting the exhaust steam from the cylinders of the engine into the feed water heater which automatically becomes operative when steam is applied to the cylinders of the locomotive 40 and which becomes inoperative when the locomotive is drifting or at rest thereby avoiding the waste of steam and preventing the formation of vacuum in the cylinders of the locomotive.

45 These and other objects I attain by the construction and arrangement shown in the accompanying drawings wherein for the purpose of illustration is shown a preferred embodiment of my invention and wherein 50 like reference characters designate like parts throughout.

In the drawings:

Figure 1 is a fragmentary side elevation partially in section showing the smoke box 55 and forward end of the boiler of the locomotive;

Figure 2 is a sectional view taken through a feed water heating coil constructed in accordance with my invention;

Figure 3 is a front elevation partially 60 diagrammatic showing the manner of connecting the exhaust steam injector;

Figure 4 is a sectional view taken through a control valve for the compressor; and

Figure 5 is a sectional view taken through 65 the water entrance of the coil showing the manner of permitting the entrance of both boiler water and injector water to the coil.

Referring now more particularly to the drawings, the numeral 10 designates the 70 smoke box of a locomotive, 11 the boiler, 12 the cylinders of the locomotive and 13 the steam chests of the cylinders. The numeral 14 designates the live steam pipes leading to the steam chests 13, and 15 designates the exhausts from the steam chests. 75

The numeral 16 indicates a steam operated pressure pump of any desired construction, the suction of which is connected by conduits 17 with the exhausts 15 from the steam 80 chests 13, the numeral 18 designating the pump end of the pressure pump. The discharge of the pump end 18 is connected by conduits 19 with an oil separator 20 and from the oil separator through a pipe 21 85 having therein a check valve 22 with a coil 23 arranged within the smoke box 10 to be heated by the front end smoke box gases.

The coil 23 preferably embodies intake 90 and discharge headers 24 and 25, the pipe 21 from the pump leading into the lower end of the intake header 24. Into the lower end of this intake header preferably lead pipes 26 with the outer ends of which communicate pipes 27 leading from the boiler, 95 a check valve 28 being provided at the connection 29 of the pipes opening from the boiler toward the coil. With the pipes 26 between the connection 29 and the header 24 communicates an injector pipe line 30 leading 100 from an injector 31. It will be noted that when the injector is operated the check valve 28 will be seated against the action of the boiler pressure preventing backing up of the injected water into the boiler. The 105 discharge header 25 has communicating therewith pipes 32 having a check valve connection with pipes 33 leading to the boiler, the check valves 34 of the connection opening toward the boiler. Supplemental 110 headers 35 are provided connected with the headers 24 and 25 by means of arcuate coil

5 pipes 36 which are independently removable in order that a leaky pipe may be readily removed from the coil. The headers 24, 25 and 35 are preferably arranged in concentrated relation and a single bank of the connecting pipes 36 employed in order that the connections of these pipes may be readily accessible and the entire surface thereof exposed to the heat of the front end of the 10 smoke box.

15 In order to provide for operation of the pressure pump 16 upon admission of steam to the cylinders 12, I provide a valve organization 37, such as shown in Figure 4 in the open position. This valve organization comprises a head 38 having a threaded tubular extension 39 adapted for engagement in a steam pipe 14. The bore of the extension 39 is in communication by means 20 of a port 40 with the interior of a cylinder 41 of which the head 38 forms one end. This cylinder is provided with an outlet 42 connected by a pipe 43 with the steam inlet of the steam end 44 of the pressure pump 16. The outlet 42 of the cylinder 41 is normally closed by means of a slide valve 25 45 which is preferably formed as an integral portion of a piston 46 sliding upon a fixed stem 47. Movement of the piston is 30 opposed by a spring 48 surrounding the stem and adjustable as to tension through medium of an adjusting nut 49 disposed at the opposite end of the cylinder from that closed by the head 38. This end of the cylinder is preferably covered by a cap 50 preventing the entrance of dirt and the like.

40 It will be seen that when steam is admitted to the cylinders of the locomotive the steam passing through the port 40 will force the piston 46 backwardly against the action of the spring 48 uncovering the port 42 and permitting the steam to pass to the steam end of the pressure pump 16. The 45 operation of the pump draws the exhaust steam from the exhaust channel of the chests and compresses the same, driving the

55 compressed steam through the separator 20 to the coil 23 where it will mingle with the water of the coil imparting its heat to the same and being condensed and passing back to the boiler through pipe 33. It is pointed out that during injector action the check valves 28 and 22 will be closed preventing the passage of water to the pump and back to the boiler. As the water is heated, it 60 passes upwardly through the coils finally passing out through pipes 32 to the boiler. Attention is directed to the fact that the withdrawal by the pump of the exhaust not only provides a heating medium for the feed 65 water within the coil 23 but assists in relieving back pressure upon the engine cylinders 12 and accordingly tends to increase the efficiency thereof.

70 It will be obvious that in employing the system hereinbefore set forth many changes are possible in the construction and arrangement of the various elements thereof and I accordingly do not limit myself to the specific structure of such elements or to the 75 arrangement thereof except as hereinafter claimed.

I claim:—

75 The combination with a locomotive embodying the usual boiler, smoke box, cylinders and chests for the cylinders, of a feed water heater disposed within the smoke box receiving water from and discharging water to the boiler, a steam pump connected with the intake end of the feed water heater, a 80 connection between the intake end of the pump and the exhaust channel of the steam chest, and a steam supply for the steam end of said pump including a connection between the live steam line to the chest and 85 the pump embodying a valve opening to permit passage of the steam from the steam line to the pump at a predetermined pressure within the steam line.

90 In testimony whereof I hereunto affix my signature.

JOHN R. SHANNON.
